SPRING CUSHION

Robert J. Beede and Herbert G. Beede,
Pawtucket, R. I.

Application August 10, 1932. Serial No. 628,244

12 Claims. (Cl. 68—9)

Our invention relates to a spring cushion pad capable of use in connection with pressing or pressure apparatus such, for instance, as ironing machines and clothing presses, in connection with which we will hereinafter describe the same.

In its broader aspects the invention contemplates the provision of a unitary structure embodying a plurality of individually yieldable elements so arranged and mounted relative to each other as to present or provide a substantially continuous flat or curved surface yieldable as a whole and in different areas according to the regularity or irregularity of the surface of an object into contact with which the surface of the yieldable unitary device may be brought under pressure.

An important general object of the invention is to provide a unitary spring cushion pad of the above type characterized by simplicity of construction, durability, and efficient operation.

One of the important specific objects of our invention is to provide a plate of any predetermined shape according to the particular purpose or device to which the pad is to be applied, and novel and effective means for connecting the yieldable devices to the plate to form the substantially continuous yieldable surface.

The foregoing and other objects and the advantages of the invention will become apparent and will be particularly pointed out during the course of the following detailed description of the accompanying drawings wherein, for the purposes of illustration, the invention is shown applied to a pressing member of a clothes pressing machine, and in which

Fig. 1 is a fragmentary view of a clothes pressing machine showing the pressing buck in perspective and with a portion of the pad and covering broken away to disclose the faces of some of the yieldable members;

Fig. 2 is an enlarged sectional view on the line 2—2 of Fig. 1;

Fig. 3 is an enlarged vertical central sectional view through one of the yieldable members and a portion of the supporting plate shown in Fig. 2;

Fig. 4 is a bottom plan view of the same yieldable member;

Fig. 5 is a plan view of a fragment of the supporting plate;

Fig. 6 is a view similar to Fig. 2 showing another embodiment of the invention;

Fig. 7 is a fragmentary bottom plan view partly in section of the spring cushion pad shown in Fig. 6;

Fig. 8 is a view similar to Fig. 3 showing the embodiment of Fig. 6; and

Fig. 9 is an exploded perspective view of the embodiment shown in Fig. 8.

Referring to Fig. 1, the numeral 10 designates generally the fixed pressing element or buck of a clothes pressing or ironing machine, which as shown in Fig. 2, includes the bottom plate 11, fabric pad 12, and cover 13. A spring cushion pad embodying our invention is shown applied between the plate 11 and the pad 12 and comprises a metallic plate 14, which, it will be understood, conforms to the shape of the plate 11 to which it may be secured by any suitable means, such as screws, not shown, but which engage in screw holes in the plate 11 at its edge in obvious manner.

Plate 14 is provided at regular spaced intervals with openings 15, which as shown in Fig. 5, resemble keyhole openings, being enlarged at their center and having alined slots 16 at opposite sides. There are also provided alined depressions 17 formed in the body of the plate marginally of the openings 15, the depressions 17 being alined in a plane intersecting the plane of the alined slot 16 for a purpose hereinafter described.

The individual yieldable spring cushion members comprises cup-shaped caps 18 preferably of rectangular form and, as shown in Fig. 4, each has an opening 19 in its end wall with depressions 20, similar to the depressions 17, in alinement at opposite sides of the opening 19. A coil spring 21 is placed in the cap with one end abutting the end wall of the cap 18 and surrounding opening 19, and its other end abuts the plate 14. To connect the cap 18 to the plate 14 with the spring in the position described and compressed between the cap and plate, we may provide a pair of staples of similar form, each comprising a U-shaped member, the lower of which is designated by the numeral 23 and the upper of which is designated by the numeral 22. As shown in Fig. 2, each of the connectors or staples 22 and 23 has its ends bent outwardly to form hooks 24 to engage or seat in the depressions 17 and 20 respectively. The relative dimensions of the depressions and hooks 24 is such that the hooks will be snugly housed in the depressions and will not project beyond the faces of the cap 18 and plate 14.

The parts are assembled as follows:

The staple 22 is inserted through the opening 19, which is of sufficient diameter to permit passage of the U-portion of the staple therethrough and the ends 24 of the staple 22 are positioned at right angles to the depressions 20. With the

105

110

staple so positioned the spring may be inserted in the cap 18 surrounding the staple 22 and the staple 23 engaged with the staple 22 in the manner shown in Figs. 2 and 3, and then the ends 24 of the staple 23 are passed through the slots 16 at which time they are at right angles to the position of the feet 24 on the staple 22 since the slots 16, when the parts are completely assembled, are in the same plane with the depressions 20 in the cap 18. Of course the cap is pressed and held toward the plate during this assembling operation and the spring is greatly compressed, but after the ends of the staples have been positioned as described the cap may be released to permit the spring to expand. The staple 23 is turned 90° until its ends are seated in the depressions 17 and the turning of the staple 23 will also effect turning of the staple 22 the same amount and bring the ends of the staple 22 in the depressions 20, so that the parts will be securely locked together. When the plate 14 is connected to the plate 11 the ends 24 of the staple 23 will be positively prevented from becoming dislodged from the depressions 17 because they will be below the surface of the plate 14 which is in contact with the plate 11. Similarly the ends of the staple 22 will be within the depressions 20 and prevented from escaping or turning therefrom, because the face of the cap 18 is in contact with the pad 12.

While we have shown the slots 16 and depressions 17 relatively positioned at right angles it should be perfectly obvious that they can be arranged at any other angle and that the amount of turning movement of the cap which seats the ends of the staples in their respective depressions will be determined by the relative angle between the slots 16 and depressions 17.

In Fig. 2, we have shown a garment G, having a button B, placed on the pressing element to illustrate how, when the pressing members are brought together individual members of the cushion pad will yield at the point where the button is positioned. This relieves pressure on the button and gives an even pressure on the garment. The strength or resiliency of the springs 21 is a matter to be determined according to the use to which the invention is put, as for some uses it may be desirable to have a stronger spring action than for others.

As previously stated, another embodiment of our invention is illustrated in Figs. 6-9 and we have there shown the said embodiment applied to the same type of pressing apparatus but illustrated in the position it occupies on the head, including the plate 11' of the pressing member and the pad 12 and covering 13, the yieldable members being housed between the pad, covering, and plate 11' as shown in Fig. 6.

The embodiment of the invention about to be described provides a substantially complete housing or casing for the springs, and, as in the case of the embodiment shown in Figs. 1-5, employs a U-shaped member to retain the cap of the housing in position with the spring in compressed condition and tending to force the cap away from the plate on which the parts are mounted. This plate is designated by the numeral 25 and has at regular spaced intervals openings 26 providing therebetween aligned portions or strips 27. The openings, when the yieldable members are secured to the plate, are paired, that is, portions of the U-shaped members, namely, the arms, are mounted through the openings, and the intermediate portion of the U-shaped members contact the strips 27 between each pair of openings. This is very

clearly shown in Fig. 8 where the U-shaped retaining members are designated generally by the numeral 28, each having an intermediate portion 29 and opposite arms with their ends bent outwardly and terminating in flanges designated by the numeral 30. The intermediate portion 29 of each of the U-shaped retaining members engages against the portion or strip 27, on one side of the plate, and on the opposite side of the plate we provide a base or part of the spring casing designated generally by the numeral 31 having side arms 32 and an intermediate portion 33 with notches 34 formed in opposite edges of the intermediate portion between the side arms 32, the notches being of a width and depth to accommodate the side arms of the U-shaped retaining members 28. Thus, when a member 31 is positioned with its intermediate portion 33 over the strips or portions 27 of the plate on the side thereof opposite to the side on which the intermediate portions 29 of the members 28 are positioned, the side arms of the U-shaped members 28 are engaged in the notches 34 so that the members 31 are accurately positioned between the openings 26 and against the portions 27 and prohibited or restrained from sliding movement in any direction. The casing for the spring 35 is completed by the cup-shaped caps designated generally by the numeral 36 including a top or end wall 37, side walls 38 having inwardly bent flanges or ends 39 and straight side walls 40 at right angles to the walls 38. In Fig. 8 the parts just described are shown in detail in assembled position with the portion 29 of the retaining members 28 in face to face relation with one side of the plate 25 over the portions 27 and with the members 31 in face to face relation with the other side of the plate and the arms 32 extending partially into the cap 36 with their ends adjacent the ends of the walls 40 of the cap and in face to face relation therewith, so that the cap is restrained by the arms 32 from movement to the left or right of the position shown in Fig. 8. The side arms of the members 28 are positioned at right angles to the side arms 32 of the members 31 and the flanges or ends 30 are engaged under the flanges 39 of the cap 36. In this position the spring is compressed but is restrained from expansion beyond the position shown, by the interlocking flanges 30 and 39. The abutment of the ends of the flanges 30 with the walls 38 also prevents sliding movement of the cap 36 in directions at right angles to the left and right of the position shown in Fig. 8. Thus, the spring is housed between the members 31, 36, and 28, with one end of the spring abutting the wall 33 of member 31, and its other end abutting the wall 37 of the cap 36. Obviously, the cap may be forced or may yield toward the plate 25 the distance between the ends of the walls 38 and the plate 25 or any portion of that distance according to the formation of the surface brought into contact with the cap 36 which may be a button or any other projection as previously explained.

The parts of the embodiment shown in Figs. 6-9 may be assembled in the following manner. The retaining member 28 is applied to the plate 25 by inserting the side arms thereof through the openings 26 and bringing the wall 29 into contact with the strip 27. The member 31 is then applied to the other side of the plate with the side arms of the member 28 engaged in the notches 34 and with the wall 33 against the strip 27. One wall 40 of the cap 36 would be bent outwardly toward the plane of the wall 37 so that the ends thereof would be in a position permitting them to pass

over the ends of the walls 32 when the flanges 39 are engaged with the flanges 30 of the member 28 with the spring 35 compressed between the member 33 and the cap 36. When the cap 36 has been moved to the position shown in Fig. 8 by sliding the flanges 39 along the flanges 30, the bent-up wall 40 will have passed over both of the walls 32 and the other wall 40 will eventually contact one of the walls 32 and stop the cap at the proper position. The wall 40 which has been bent out to permit passage thereof over the walls 32 is then bent at substantially right angles to the top 37 and in substantially the same plane as the wall 32 and partially overlapping said wall 32, whereby the cap is maintained in proper position against displacement in any direction.

In both embodiments of the invention as apparent from Figs. 1, 2, 6, and 7, it will be noted that the invention provides a substantially continuous surface yieldable as a whole or in part at areas contacted by irregular projections on matters which the surface contacts under pressure, and it should be obvious that if the device to which the plates carrying the yieldable members has a curved surface that the plate carrying the yieldable members may be curved to correspond to said surface without disturbing the regularity of the substantially continuous yieldable surface of the spring cushion device.

We have not deemed it necessary to disclose a means of attaching the unitary spring cushion device above described to a supporting member, because this is a mechanical detail and may be accomplished in several manners such as by screws or bolts engageable through the plate adjacent its marginal edges or by any other means. The device can be made in many shapes and sizes and adapted to various uses, and it should be apparent that the embodiment of Figs. 1-5 may be used on the movable pressing element or head, and that of Figs. 6-9 on the buck, the embodiments being shown respectively on buck and head merely for the purposes of illustration.

We claim:

1. A spring cushion device of the character described comprising a plate provided with a plurality of openings spaced at regular intervals, a U-shaped member having portions extending through each of said openings and having portions disposed on each side of the plate, a cap over each of said U-shaped members on one side of the plate, means carried by each of said caps and engaging said U-shaped members to hold the caps on the plate, and a coil spring between each cap and the plate urging the cap away from the plate, said engaging means and U-shaped members restricting the movement of the caps away from the plate but permitting approaching movement of the caps toward the plate under pressure.

2. A spring cushion device of the character described comprising a plate for attachment to a supporting surface and having a plurality of regularly spaced openings, U-shaped members mounted to extend through said openings and having portions disposed on the face of said plate confronting said surface and portions extending through said openings above the other face of the plate, a cap mounted above each of said U-shaped members, means on the cap engageable with said last portions of the U-shaped members to secure the cap thereto, and a coil spring between said cap and said plate normally pushing the cap outwardly from the

plate and urging said means and portions of the U-shaped members into contact to restrict outward movement of the caps.

3. A spring cushion device comprising a plate having a plurality of openings, a cap above each of said openings, a spring between each of said caps and the plate tending to push the cap outwardly from the plate, and a pair of cooperating U-shaped members each having offset ends engageable respectively with the cap and with the plate and restricting movement of the cap away from the plate under the action of said spring and permitting approach of the cap toward the plate under force exerted to compress said spring.

4. The structure of claim 3 wherein the cap and plate each have depressions to receive the offset ends of the U-shaped members and said depressions in the respective parts being arranged in intersecting planes whereby turning movement of one of said U-shaped members to seat the offset portions in its depressions will exert a turning movement on the other member and seat its offset ends in the depressions on the other members.

5. A spring cushion device comprising a plate having a plurality of regularly spaced openings with marginally disposed aligned notches on opposite sides of each opening, a U-shaped member having offset ends insertable through said notches, depressions at opposite sides of each opening in a plane intersecting the plane of the notches to receive said offset ends after the same had been inserted through said notches and the U-shaped member turned, a cap above said opening, a spring between said cap and the plate, and means carried by the cap engageable with said U-shaped member to hold the cap above the plate against the action of said spring.

6. The structure of claim 5 wherein the means carried by the cap comprises a second U-shaped member having offset ends, said member being insertable through an opening in the cap and said cap has depressions at opposite sides of said opening in substantial alignment with the notches in the opening in the plate and in a plane intersecting the plane of the depressions in the plate.

7. A spring cushion device comprising a plate having a plurality of regularly spaced openings, a U-shaped member having opposite arms extending through a pair of said openings with its middle portion against the material of the plate between said openings, the upper ends of said U-shaped members being bent outwardly, a cap above said portion of the plate between the openings and having depending side walls with inwardly bent ends engaging the bent ends of the U-shaped member to restrict movement of the cap away from the plate, and a spring between the cap and the plate normally urging said cap outwardly from the plate and maintaining said bent ends in engagement with each other.

8. A spring cushion device comprising a plate having a plurality of regularly spaced openings, a U-shaped member having opposite arms extending through a pair of said openings with its middle portion against the material of the plate between said openings, the upper ends of said U-shaped members being bent outwardly, a cap above said portion of the plate between the openings and having depending side walls with inwardly bent ends engaging the bent ends of the U-shaped member to restrict movement of the cap away from the plate, and a spring between the cap and the plate normally urging said cap outwardly from the plate and maintaining said bent ends in engagement with each other.

the cap and the plate normally urging said cap outwardly from the plate and maintaining said bent ends in engagement with each other, and means preventing lateral movement between the 5 cap and U-shaped member.

9. A spring cushion device comprising a plurality of individually mounted adjacent yieldable members presenting a substantially continuous yieldable surface, said members being mounted 10 on a supporting plate and each including an element engaging with the plate, and an element in engagement with said first element, and having a surface forming part of said substantially continuous surface, spring means urging said second 15 element away from said plate, and means on said elements slidably engageable to secure them together and limit movement of said second element away from said plate.

10. A spring cushion device comprising a plurality of individually mounted adjacent yieldable members presenting a substantially continuous yieldable surface, said members being mounted on a supporting plate and each including an element engaging with the plate, and an element 25 in engagement with said first element, and having a surface forming part of said substantially continuous surface, spring means urging said second element away from said plate, means on said elements slidably engageable to secure them together and limit movement of said second element away from said plate, and preventing relative lateral movement between said parts in opposite aligned directions, and means preventing 30 relative lateral movement between said parts in opposite aligned directions intersecting the line of 35 said first directions.

11. A spring cushion device of the character described comprising a plate and plurality of yieldable members mounted thereon and presenting a substantially continuous surface, each of said members comprising an element having arms inserted through openings in the plate, an element on the plate and held against lateral movement by the arms of said member, said element also having arms at opposite sides of said member and at substantially right angles to said first arms, a cap having walls terminating adjacent the ends of said arms on the element and member, a spring normally urging said cap away from the plate, and means limiting the movement of the cap away from the plate. 80

12. A spring cushion device of the character described comprising a plate having a plurality of yieldable elements thereon presenting a substantially continuous surface, each of said elements comprising a cap having a surface forming part of said substantially continuous surface and having side walls, two of said walls having lateral projections confronting each other, a member holding said cap on the plate and having lateral projections on opposite walls to engage said projections on the cap walls, elements on the plate at the ends of said opposite walls and overlapping other opposite walls on the cap to prevent sliding movement between said cap and member after assembly, and a spring normally urging said cap away from the plate and said projections on the cap and member into contact with each other. 90
